W. C. SUMMER ET AL

COMBINED TOILET FAN AND HAIR DRIER

Filed Dec. 9, 1920

Inventor
Walter C. Summer
William L. Minick, Jr.

Elmer R. Ford

Attorney

UNITED STATES PATENT OFFICE.

WALTER C. SUMMER AND WILLIAM L. MINICK, JR., OF WAYNESBORO, PENNSYLVANIA.

COMBINED TOILET FAN AND HAIR DRIER.

Application filed December 9, 1920. Serial No. 429,560.

To all whom it may concern:

Be it known that we, WALTER C. SUMMER and WILLIAM L. MINICK, Jr., citizens of the United States, residing at Waynesboro, in the county of Franklin and State of Pennsylvania, have invented certain new and useful Improvements in Combined Toilet Fans and Hair Driers, of which the following is a specification.

10 Our invention relates to a combined toilet fan and hair drier, and has for its object to provide a fan which can be attached to any of the closets now in ordinary use.

15 Another object is to provide a toilet fan which can be operated by the ordinary electric current such as is used for electric lights and the like.

Another object is to provide a toilet fan 20 that can take care of a number of closets.

Another object is to provide a fan which takes up little space, which is easily kept clean, and which is ornamental rather than the reverse.

25 Another object is to provide a hair drying attachment in connection with a toilet fan.

Referring to the accompanying drawings, which are made a part hereof and on which 30 similar reference characters indicate similar parts,

Figure 1 is a side elevation showing our devices in position for use,

Figure 2, a longitudinal section through 35 the connection with the flush pipe,

Figure 3, a longitudinal section through the connection to the hair drying tube.

In the drawings reference characters 10 indicate a toilet bowl of ordinary construction, having a flush pipe 11 leading to the usual water openings from a tank 12. A fan 13 is connected at any convenient point to the flush pipe by a pipe comprising three sections 13', 14 and 14' connected by ordinary unions.

40 These sections may be connected to the fan and flush pipe respectively by any ordinary and convenient means, and one union may have a valve 30 similar to the valve in Figure 3. In Figure 2 the pipe 14 is shown as being connected to pipe 11 in the ordinary manner by cutting a hole in pipe 11, cutting the end of pipe 14 to fit and wiping the joint in the ordinary manner.

45 They may be connected in other ways as by inserting pipe 14 through the hole, placing a cap thereabout and soldering it to both

of the pipes, or by making part 14 in one piece with a section of pipe of the size of the flush pipe. In new installations, the entire flush pipe might be made with 14 50 as a projection therefrom.

The outlet pipe 15 from the fan communicates with the outer air by connection to the usual vent pipe, a chimney or other opening.

55 The pipe 15 has a union 16 inserted intermediate of its length, and this union is formed with an extension 17 for connection thereto of a tube 18 with a mouth piece 18'. A valve 19 in the union 16 is adapted to 60 close an opening leading to tube 18 or an opening leading to the outer section of pipe 15.

65 At or near the joint between pipes 11 and 14 there is pivoted a circuit breaker 20, which may be weighted as at 21 or may be moved in one direction by a spring if desired, so as normally to maintain the circuit breaker in closed position. A member 22 separated from the pipe by a block of insulating material 23 serves as the second member of the circuit closing and breaking device. A wire 24 is connected to member 22, and member 20 is connected through the pipe 11 to a ground 25. At the other side 70 of the circuit is a wire 26 with a manually controlled switch 27 interposed between its parts. This wire is connected to the fan motor which in turn is connected to a ground 28.

75 In operation the switch 27 is closed and the fan will run continuously drawing air through pipes 11, 14 and 14' from bowl 10 and the air passing through the fan and out by pipe 15. When the bowl is flushed, the 80 down-flowing water strikes circuit breaker 20 and swings it away from part 22, breaking the circuit at this point and stopping the fan until the flow of water ceases when weight 21 returns part 20 and the circuit 85 is again completed until switch 27 is again opened.

85 If the hair drying device is to be used it is merely necessary to close the switch 27 and move the valve 19 by its handle 19' 90 into the dotted line position as shown in Figure 3, and valve 30 to a similar position when the fan will draw air through the pipe 13' and blow out through tube 18 and mouth piece 18'.

95 Various changes and modifications will occur to those skilled in the art and we do 100 110

not limit ourselves to the precise form of the invention as shown and described, the true scope of the invention being shown by the appended claims.

Having thus fully described our said invention, what we claim as new and desire to secure by Letters Patent, is:

1. A toilet fan attachment comprising a bowl, a flush tank, a pipe connecting them, a fan adjacent the bowl, an electric switch adjacent said pipe for controlling the operation of the fan, a second pipe attached to the first and connecting the fan thereto to draw air from the bowl, means for connecting the outlet side of the fan casing to the outer air, and means whereby said switch is operated by the flow of water from the flush tank to the bowl to stop the fan, substantially as set forth.
2. A toilet fan attachment, comprising a bowl, a flush tank, a flush pipe, a branch pipe attached to the flush pipe for withdrawing air therefrom, a fan in communication with the second pipe means for driving the fan, and means for stopping automatically the fan while the bowl is being flushed, substantially as set forth.
3. A toilet fan attachment, comprising a bowl, a flush tank, a flush pipe, a fan connected to the flush pipe for withdrawing air therefrom, a motor for driving said fan and means operated by water in the flush pipe to interrupt the action of the motor, substantially as set forth.
4. A toilet fan attachment, comprising a bowl, a flush tank, a flush pipe, a fan connected to the flush pipe for withdrawing air therefrom, an electric motor for driving the fan, electrical connections from a source of power to the motor and means for interrupting the action of the motor comprising a switch in said connections, adapted to be operated by flowing water, substantially as set forth.
5. The combination of a bowl, a flush tank, a pipe connecting them, a second pipe connected to the first and to the outer air, means for producing a suction in the pipes to draw air from the bowl, and an electric switch operated by the flow of water in the flush pipe to interrupt the action of said suction means, substantially as set forth.
6. In a toilet attachment, a fan, an intake pipe attached thereto and adapted to be connected to a flush pipe, an outlet pipe adapted to communicate with the outer air, a tube attached to the latter pipe having a

free end, and means in said pipes whereby the fan may operate either to draw air from the bowl, or to forcing air out of the free end of the tube, substantially as set forth.

7. In a toilet attachment, a fan adapted to be connected to a bowl to draw air therefrom, an exhaust pipe communicating with the outer air, a flexible tube also connected to the fan, said tube also having a free end and means for alternatively admitting the current from the fan to the exhaust pipe and the flexible tube, substantially as set forth.

8. In a toilet attachment, a fan, an intake pipe attached thereto and adapted to be connected to a flush pipe or to the air in the room, an outlet pipe adapted to communicate with the outer air, and a tube attached to the outlet pipe and having a free end adapted for use as a hair drier, substantially as set forth.

9. The combination of a flush tank, a bowl, a pipe connecting them, a fan connected to the pipe and to the outer air, a motor to drive the fan and a circuit closer for the circuit of the motor comprising a stationary element, and a pivoted element coacting therewith and extending into the flush pipe in position to be operated by the flowing water, substantially as set forth.

10. In a toilet appliance, an electric fan, a casing therefor, a pipe connecting said casing to a flush pipe, a union between two parts of said pipe having a passage leading into the room, a valve adapted to open alternatively the passages to the flush pipe and the room, a pipe connecting the fan casing to the outer air, a union between two parts of said pipe having a lateral passage, a relatively long flexible pipe leading from said lateral passage and adapted for use as a hair drier, and a valve adapted to open alternatively the passages to the outer air and to said lateral passage, whereby a single fan is adapted to operate the hair drying attachment and also to act as a toilet fan, substantially as set forth.

In witness whereof we have hereunto set our hands and seals at Waynesboro, Pennsylvania, this 15th day of October, A. D. nineteen hundred and twenty.

WALTER C. SUMMER. [L. S.]
WILLIAM L. MINICK, JR. [L. S.]
